VACUUM-TUBE CIRCUITS

Application filed November 30, 1937. Serial No. 236,714.

This invention relates to space discharge vacuum tubes, particularly to methods of operation thereof wherein the relation existing between the fundamental frequencies and the products of modulation in the output circuit of a vacuum tube can be regulated.

Heretofore in modulating systems employing vacuum tubes in which the production of the modulation component was considered as occurring in the plate circuit, the modulating action has been attributed to a non-linear relation existing between either the plate voltage and plate current or the grid voltage and plate current. In such cases the modulation has been considered as due entirely to the resistance variations in the space path of the tube, conveniently termed R_o modulation.

When a vacuum tube is used as an amplifier its operation is usually restricted to the so-called straight portion of the plate current-grid voltage characteristic curve. If the curve were actually straight it is apparent that distortionless amplification free from the effects of modulation would result. Such an ideal condition has never been produced in a single vacuum tube amplifier although in special circuits it has been found possible to eliminate certain of the modulation products.

In dealing with the operation of a vacuum tube both as an amplifier and as a modulator, the amplification factor μ has generally been considered constant although in practice a variation has been found to exist depending on changes in the values of grid and plate voltage which, however, it has been the practice to disregard.

This variation in the amplification factor has been found to be responsible for additional products of modulation in the vacuum tube output circuit independent of the R_o modulation. This action will be termed μ modulation.

In accordance with an object of the present invention the modulation current present in the output of a vacuum tube is controlled by regulating the amplitude and phase of the R_o modulation and the μ modulation.

Another object of this invention is to con-

trol the ratio of the modulation products to the fundamental product in the output of the space discharge vacuum tube by the proper selection of values of grid biasing potential, plate potential, plate circuit resistance and alternating grid potential. 55

Another object of this invention is to determine for any space discharge vacuum tube the conditions of operation under which the ratio of second order modulation currents to fundamental current will attain its smallest possible value. 60

Still another object of the invention is to operate a vacuum tube so that the second and third order modulation products are reduced or eliminated. 65

Another object is to facilitate the selection of a vacuum tube together with its conditions of operation which will operate at prescribed power and modulation levels with a minimum expenditure of direct current power. 70

Another object of the invention is to approach an ideal amplifier.

Still another object of the invention is to increase the power output of a vacuum tube amplifier without increasing distortion. 75

A feature of the invention involves regulating the value and phase of the components of modulation in a vacuum tube due to the μ modulation and R_o modulation with respect to each other whereby a desired ratio of modulation products to fundamental product is obtained. 80

Another feature is the use of a four-element vacuum tube with the circuit potentials adjusted to such values that the μ modulation and R_o modulation are equal and of opposite phase so that an amplified wave substantially free from distortion by modulation products, results. 85

Heretofore characteristic vacuum tube equations expressed the output current of a vacuum tube as a function of grid and plate potential. The plate current was considered as composed of a constant component due to the source of plate potential and a number of components due to a variable potential in the grid circuit. When only one variable is considered, namely, grid potential, the tube char- 95

acteristic equation expressing plate current as a function of the variable grid potential is a power series involving this variable.

For many practical purposes analysis by the above method is fairly satisfactory but where the requirements with respect to modulation are particularly severe as, for instance in multi-channel repeaters, the assumption of the constant μ may not be sufficiently accurate. In fact it has been shown that in the normal operation of the vacuum tube amplifier where the grid potential is always negative and where the greatest applied negative potential does not exceed the most negative end of the grid potential plate current characteristic curve, variation in μ has been as large as 20% over the operating range. The effects of this μ variation which have heretofore been neglected are determined and utilized by the methods of this invention.

Since the main object of this invention is the control of the ratio of modulation products to the fundamental products a determination of the factors affecting the products of modulation is essential. In the theoretical development of the expressions for the modulation products, account is taken of the variations in the amplification factor μ . The accuracy of the theory is substantiated by the close agreement of the calculated with the experimental results.

In the practice of the invention it is first necessary to consider the expressions affecting the values of the various products of modulation. As indicated hereinbefore, products of modulation refer to the currents of combination frequencies which are present in the output circuit of a vacuum tube due to variations in amplification factor μ (μ modulation) and in the internal plate resistance of the tube R_o (R_o modulation). The new expressions developed by applicants giving coefficients of the modulation products are derived by representing the characteristic tube equation as a double power series and have been developed in terms of the amplification factor μ , the internal resistance of the tube R_o , and their differential parameters.

The derivation referred to above is given in an article by the applicants in the July 1927 issue of the "Bell System Technical Journal". Herein the fundamental and second harmonic currents are given by the equations

$$J_1 = C_1 E$$

$$J_2 = \frac{C_2 E^2}{2} \quad (1)$$

where $C_1 = \frac{\mu}{R_o + R}$

$$C_2 = \frac{C_1}{2\mu} \left[\frac{\delta\mu}{\delta E} - C_1 (R - R_o) \frac{\delta\mu}{\delta E} - R_o C_1^2 \frac{\delta R_o}{\delta E} \right] \quad (2)$$

In these equations E denotes peak value of

the E. M. F. impressed upon the grid, J_1 and J_2 the peak values of the fundamental and second harmonic currents, μ the amplification factor at the operating point, R_o the corresponding value of the internal resistance, and R the external resistance in the plate circuit.

The derivation of the above relations involves the consideration of two variables, namely μ and R_o . The same treatment may be extended to tubes having characteristics depending upon a larger number of variables. Thus a four-element double grid tube characteristic may be expressed by a triple power series, etc.

If the potential of one of the grids of a four-element tube be held constant the relation for three-element tubes may be used so that the expression given for C_1 and C_2 will apply. Four-element tubes will be considered in a later part of this specification.

From the relations given in Equations (1) and (2) the ratio of second harmonic to fundamental current in vacuum tubes and the behavior of this ratio as a function of the four independent variables, namely, (a) alternating grid potential or grid swing, (b) plate circuit resistance, (c) grid potential, (d) plate potential, can be determined. From these results an amplifier tube which is required to meet prescribed conditions in a given circuit may be selected.

A better understanding of the invention may be had from the following description in conjunction with the accompanying drawings of which Fig. 1 shows a three-element vacuum tube used in an ordinary amplifier circuit. Fig. 2 shows a special four-element vacuum tube used as an amplifier in accordance with the invention. Figs. 3 to 14 are curves showing tube characteristics and experimental results which will be referred to as the description of the invention proceeds.

The relations given by the Equations (1) and (2) will first be considered in connection with three-element vacuum tubes connected in the simple amplifier circuit such as that shown in Fig. 1. Herein the three-element vacuum tube 10 has an output circuit associated therewith which can be traced from the plate 1, to a source of plate potential which is here represented by battery 6, through the resistance 5, the cathode 3, back to the plate 1 through the space path of the tube. The input circuit can be traced from the grid 2 to the cathode 3 through a suitable means for impressing an alternating wave upon the input circuit such as transformer 4. Some means such as a battery 9 is provided for maintaining a biasing potential upon the grid. An alternating wave is provided in any well known manner from a source 8.

Since the various modulation products of a given order are related in a simple manner, the present discussion as regards modulation

products, will be limited to the harmonics of a single impressed frequency. It is assumed that the plate circuit impedance R is a pure resistance which is the same at all frequencies, that the plate current is never reduced to zero, and that the grid current is always negligible.

In order that the invention may be more readily understood the equations which illustrate the operation of the vacuum tubes will first be discussed for various conditions of operation after which the methods of selecting the correct circuit parameters for obtaining the desired conditions will be illustrated by means of experimental data. Conditions of operation for which the ratio of the second order modulation product to fundamental attains its smallest possible value will be discussed first. These conditions have been determined for two distinct cases. In the first case the load resistance is restricted to equal the tube resistance whereas in the second case no restriction is placed on the load resistance.

Letting Δ denote the ratio of second order modulation product to fundamental it follows from Equations 1 and 2 given above that

$$30 \quad \Delta = \left[\frac{\delta\mu}{\delta E_s} - C_1(R - R_0) \frac{\delta\mu}{\delta E_s} - R_0 C_1^2 \frac{\delta R_0}{\delta E_s} \right] \frac{E}{4\mu} \quad (3)$$

For the case in which the two impedances match the Equations 2 and 3 become:

$$35 \quad C_1 = \frac{\mu}{2R_0}$$

$$C_2 = \left[\frac{\delta\mu}{\delta E_s} - \frac{\mu^2}{4R_0} \frac{\delta R_0}{\delta E_s} \right] \frac{1}{4R_0} \quad (4)$$

$$40 \quad \Delta = \left[\frac{\delta\mu}{\delta E_s} - \frac{\mu^2}{4R_0} \frac{\delta R_0}{\delta E_s} \right] \frac{E}{4\mu} \quad (5)$$

From Equation 1 the output fundamental power is seen to be

$$45 \quad W = 1/2(C_1 E)^2 R \quad (6)$$

Referring to Equation (2) it is seen that the determination of the modulation coefficient C_2 requires the evaluation of three partial derivatives in the general case, for which $R^2 R_0$. These derivatives may be obtained graphically from the tube characteristics, practical examples of which are shown for one type of tube in Figs. 3 to 5. From these data the values of the fundamental and modulation coefficients C_1 and C_2 may be computed with the aid of Equations (1) and (2) for various values of grid potential, plate potential and external plate circuit resistance. These results are shown plotted on Figs. 6 to 8 inclusive. For each of these families of curves the external resistance is constant. Referring to Fig. 8, for example, it is seen that under the condition of constant load resistance, the ratio of the modu-

lation to fundamental coefficient increases rapidly as the negative grid potential is increased. This effect is less pronounced at the higher plate potentials, due to the greater constancy of that component of modulation which results from the variation of the internal resistance of the tube. This is evident from Fig. 5 for if the variation in the slope of these curves at 240 and 120 volts plate potential is compared; at 120 volts the slopes are more variable with grid potential than at 240 volts. It is also seen from the curves of Fig. 7 that for a constant value of fundamental the modulation products will decrease as the plate potential is increased. For example, if the tube is being operated at a negative grid potential of 24 volts and plate potential of 120 volts, the curves show that if the plate potential is increased to 240 volts and the negative grid potential to 65 volts, the fundamental output (for the same alternating grid voltage) will be left unchanged, but the modulation products will be reduced by about 7 T. U. The curves of Fig. 6 and Fig. 8 show similar results for two other values of load resistance. Similar conclusions apply to other tubes as may be ascertained by determining the tube characteristics and computing the values of the fundamental and modulation coefficients C_1 and C_2 as in the case herein described.

It is interesting to note that in the case of high external resistance in the circuit of the tube under consideration the second order product of modulation will pass through a minimum value as the negative grid potential is increased. This is shown in Fig. 6. The explanation is obtained by an examination of the terms in the relation for C_2 as given in Equation (2). From Fig. 4 it is seen that the first term of the equation

$$\frac{\delta\mu}{\delta E_s}$$

is practically constant as the grid potential is varied. Figs. 3 and 5 show that

$$\frac{\delta\mu}{\delta E_s} \text{ and } \frac{\delta R_0}{\delta E_s}$$

both increase as the negative grid potential increases. The effect of these characteristics upon the modulation products is seen in the relation for C_2 , for as the negative grid potential is increased the component of modulation due to the μ variation will become smaller while the component due to R_0 will increase. A certain value will be reached where the modulation introduced through the variation of R_0 will be the dominating factor thereby accounting for the minima shown in Fig. 6. It is only for high external resistances that these minima appear since it is only in such cases that the second term of the expression for C_2 is appreciable.

Although an examination of a large variety of tubes disclosed that the ratio of second order modulation products to fundamental decreases for all cases, when the plate potential or the negative grid potential was increased, one type of three-element tube was observed which showed a minimum value of modulation as the negative grid potential was increased. This is accounted for by the different way in which μ varies in the different tubes.

It will now be shown how, by means of the families of curves such as those of Fig. 6, it is possible to select a tube, together with its operating potentials and load resistance, which will yield a given power output with a minimum amount of modulation. The problem is somewhat simplified if the alternating grid potential is supposedly fixed. This may be illustrated by means of the following simple example:

Suppose that with a given grid swing of 40 volts (peak value) it is required to select a tube, together with its grid potential, plate potential and load resistance which will yield an output level of 0.2 watt with a minimum amount of second harmonic. It is first necessary to examine the output characteristics of a number of tubes to determine which one for the given grid swing must be selected in order to confine operation to the characteristic and prevent the grid from becoming positive. For the sake of convenience, the requirements of the problem are such as will adapt themselves to the characteristics of the tube already given. It is to be noted however, that the method is adaptable to any type of tube. First, suppose the tube to work into a resistance of 2500 ohms. In this case it is evident on solving Equation (6) for C_1 that this coefficient must be 0.316×10^{-3} . Referring to Fig. 7, it is seen at once for this value of C_1 the ratio of C_2 to C_1 will be a minimum and equal to 5.7×10^{-3} when a plate potential of 240 volts and a negative grid potential of 85 volts are used. In a similar way it is found from Fig. 8 that when an external resistance of 6,000 ohms is used a plate potential of 240 volts and a negative grid potential of 90 volts should be used, in which case the ratio of C_2 to C_1 is 3.68×10^{-3} . Finally, if an external resistance of 15,000 ohms is used, it is found from Equation (6) and Fig. 6 that a plate potential of 240 volts and a negative grid potential of 66 volts should be used, in which case the ratio of C_2 to C_1 is 0.8×10^{-3} . Hence, in order to obtain an output level of 0.2 watts with a grid swing of 40 volts, a tube of the type discussed should be used, the plate potential being 240 volts, the negative grid potential 66 volts, and the load resistance 15,000 ohms. For these values the reduction of the second harmonic below the fundamental is found from Equation (1) to be 36 T. U. This ratio could probably be

improved still more by increasing the load resistance and decreasing the negative grid potential, as may be determined by calculating the modulation coefficient for greater values of load resistance.

The foregoing relations will now be considered with respect to four-element (double grid) tubes. It has already been pointed out that if one of the grids is maintained at a constant potential the tube characteristic equation can be expressed by a double power series and the expressions for the modulation coefficients C_1 and C_2 as given above will apply.

It may be shown that the modulation products may be reduced to a minimum and in fact may be made to vanish for all practical purposes in a tube having two grids, one of which is maintained at a constant positive potential with respect to the cathode, the three remaining elements being used as an ordinary vacuum tube.

Such a tube is shown in Fig. 2, which illustrates the tube as it would be used in an amplifier circuit. Therein tube 30 is a four-element vacuum tube having an anode 31, a cathode 34 and two grids 32 and 33. One grid 33 is maintained at a constant positive potential with respect to the cathode 34 by means of a source of potential 38. In all other respects the circuit is similar to that shown in Fig. 1. In order to avoid confusion the constant potential grid will be referred to as the fixed grid and the other one as the varying grid. The voltage upon the fixed grid will be denoted by E_{fg} while alternating voltage impressed upon the varying grid will be called E_{vg} .

In a manner similar to that used in connection with the three-element tubes, families of curves must be drawn in order to evaluate the modulation coefficients C_1 and C_2 . Fig. 9 shows a group of curves in which the amplification factor μ is plotted as a function of E_{vg} , the varying grid potential, for various values of voltage on the fixed grid, plate potential being held constant. At other values of plate potential the amplification factor is slightly lower but the variations with varying grid and fixed grid potential is very nearly the same.

Figs. 10 and 11 show the internal resistance R_o plotted as a function of plate potential for various values of negative bias upon the varying grid, the potential upon the fixed grid E_{fg} being maintained at 40 volts. These curves are also a typical group, the corresponding groups for lower fixed grid potentials being very similar especially as to the change of slope from positive to negative as the varying grid potential is increased.

From these results fundamental and second order coefficients may be calculated by means of Equation 2 in which for double grid tubes E_o is given as E_{vg} . If the load resistance is

adjusted to match the tube resistance, that is, $R = R_0$, the second term of the expression C_2 drops out and there remain two terms due respectively to the variation of μ and to the variation of R_0 . It becomes necessary then if the second order modulation is to vanish, for the μ and R_0 modulation to be equal and of opposite sign. A group of curves of the calculated second order coefficient as a function of the varying grid voltage, for various values of plate voltage, the fixed grid potential being the same for all cases is shown by Fig. 12. These curves show that for each plate voltage there is at least one value of varying grid voltage for which the second order coefficient vanishes and in one case there are three such points. It can be shown that the curves for other values of fixed grid voltage, other conditions remaining the same are all similar to these. These curves demonstrate that the second order currents should reverse in phase as the varying grid voltage is varied through one of the vanishing points. This is due to the variation in the factors expressing the μ modulation and the R_0 modulation since it is evident from Equation (2) that, as the smaller component becomes equal and then exceeds the other, the sign of the coefficient C_2 changes denoting a change in phase of the resultant modulation current.

As pointed out above Fig. 12 shows that for one set of circuit conditions there are three values of grid potential at which the second order coefficient becomes zero. The curve of Fig. 13 shows the calculated relation of the first harmonic current to the varying grid swing as determined from Equation (1) for the same circuit conditions. Likewise for the same conditions a curve showing the measured relation of the third harmonic and varying grid swing is shown in Fig. 14. A comparison of these three curves representing fundamental and the second and third order products of modulation reveals that when the second order product is zero at one point the third order product is practically zero while the fundamental is almost at its maximum value. It can be shown by comparison that the calculated and measured values of current for the above relations are in close accord.

To summarize it can be shown from the expressions for the coefficients of the modulation products that their value can be regulated by properly selecting the circuit parameters, that having determined the tube characteristic curves, the operating points which give a minimum value of second and third order modulation products can be selected, and in some type of vacuum tubes the higher order modulation products can be made to vanish and in one type of tube used, at the point of maximum fundamental output.

Although this invention has been described in connection with particular types of tubes, it is nevertheless capable of broad application and is to be limited only by the scope of the appended claims.

What is claimed is:

1. In a space discharge circuit, a space discharge device having electrodes, an input and an output circuit associated with said electrodes, a resistance in said output circuit, means for applying a wave to the input circuit to be repeated, means for applying operating potentials to the input and output electrodes, the magnitudes of the operating potentials being proportioned (for a given peak amplitude of the input wave) with respect to each other to control the ratio of output modulation component to output fundamental component and both said magnitudes being proportioned with respect to the external output resistance to control the output of useful components.

2. In a space discharge circuit, a space discharge device having electrodes, an input and an output circuit associated with said electrodes, a resistance in said output circuit, means for applying potentials to said electrodes, the values of said resistance and said potentials being proportioned so that the ratio of the modulation products to the fundamental products is a minimum.

3. In a space discharge circuit, a space discharge device having electrodes, an input and an output circuit associated with said electrodes, a resistance in said output circuit, means for applying potentials to said electrodes, the values of said resistance and said potentials being proportioned so that the ratio of the modulation products to the fundamental products is zero.

4. In a space discharge circuit, a space discharge device having electrodes, an input and an output circuit associated with said electrodes, means for regulating potentials applied to said electrodes, means for applying a wave of alternating potential to said input circuit to be repeated, means for repeating said wave in said output circuit together with components of modulation resulting from the changing amplification factor and the changing internal resistance of said discharge device, said regulating means causing a predetermined relation to exist between said varying amplification modulation component and said varying internal resistance modulation component.

5. In a space discharge circuit, a space discharge device having four electrodes, means for applying potentials to said electrodes, said potentials being proportioned with respect to each other at such values that modulation due to the varying amplification factor of said space discharge device substantially balances the modulation resulting from

- the varying plate resistance of said space discharge device.
6. In a space discharge circuit, a space discharge device having four electrodes, an output circuit associated with two of said electrodes, a resistance in said output circuit, means for applying potentials to said electrodes, the values of said potentials and said resistance being proportioned to effect reduction of modulation components relative to fundamental components by causing certain inherent tendencies toward production of modulation components to counteract each other in controllable amount.
15. 7. In a space discharge circuit, a space discharge device having an anode, a cathode, a grid electrode and a control electrode or net, an output circuit including a resistance associated with said anode, means for applying potentials to said electrodes, means for applying a wave of alternating potential to said control electrode to be repeated, means for repeating said wave in said output circuit together with components of μ modulation and R_o modulation, the values of said resistance and said potentials being regulated to predetermine the value and phase relation of the μ and R_o modulation.
8. The method of operating a space discharge device which comprises proportioning its circuit parameters to effect a predetermined relation between the μ modulation components of current and the R_o modulation components of current.
35. 9. The method of operating a space discharge amplifier to prevent distortion which comprises generating a component of modulation due to the variable amplification factor μ and another component of modulation due to the variable space resistance R_o , and regulating the value and phase of the even order modulation components so that they are substantially equal and opposed to each other.
45. 10. The method of operating a space discharge amplifier which has electrodes and input and output circuits associated with said electrodes which comprises applying a wave of alternating potential to said input circuit to be amplified, proportioning the values of operating potentials applied to the input and output electrodes relative to each other to give substantially minimum modulation products relative to fundamental products and at the same time proportioning the values of both of said operating potentials with respect to the external output resistance to give the required power output.
60. 11. The method of operating a space discharge device having electrodes, input and output circuits associated therewith, said output circuits having resistance which comprises controlling the ratio of output modulation products to output fundamental component by proportioning the input and output
- operating potentials with respect to each other and at the same time controlling the useful power output by proportioning both of said operating potentials with respect to the external output resistance.
12. In the operation of a double grid tube in which a fixed potential is applied to one grid and a wave to be repeated is applied to the other grid, the method of reducing in the outgoing circuit both even and odd order modulation products which comprises proportioning the operating potentials applied to the tube electrodes with respect to the attached output impedance to values corresponding substantially to the minimum points on the even and odd order modulation characteristics and at the same time to a high value of fundamental output.
- In witness whereof, we hereunto subscribe our names this 22nd and 26th days of November, A. D. 1927.
